ELECTRIC PLUG

Michael A. Rollman, Mount Joy, Pa.

Application February 23, 1933, Serial No. 658,182

3 Claims. (Cl. 173—322)

The object of this invention is to provide the plug with a handle which may be used for pulling it out of and putting it into the socket, to thus relieve the conductor proper of strain, this handle being laterally flexible so as to protect the corded conductor from injury by frequent sharp bending at the point of connection with the usual plug proper or cap as more fully hereinafter set forth.

10 My present invention has particular reference to improvements on the electric plug covered by my former Patent No. 1,810,439, dated June 16, 1931. In the drawing:—

15 Fig. 1 is a side elevation of my device complete.

Fig. 2 is a longitudinal sectional view of the device.

Fig. 3 is a detail view of the thimble or ferrule; and

20 Fig. 4 is a view partly in side elevation and partly in longitudinal section, showing my device applied to the plug at the appliance-end of the cord.

25 Referring to Figs. 1, 2 and 3 of the drawing annexed by reference characters, 5 designates the body or cap of the plug which carries in the usual manner the two terminals 6 adapted to enter the usual slots in the usual wall socket. The cap 5 is provided with a central passage through which the corded conductor 8 passes, the two wire conductors enclosed therein being respectively connected to the usual winding screws in the cap.

30 The cap 5 is moulded, as usual, out of some insulating material, and imbedded in the outer face of the cap in the moulding operation is a collar 10 of metal or some hard insulating material. This collar is anchored rigidly in the cap, and in order to insure against rotation of the cap the collar is provided with an annular milled bead 11 at its buried end. This collar is interiorly threaded to receive the screw thread-like cord armor 12 of the usual construction. This armor 12 is screwed into the collar 10 until its inner end is approximately flush with the inner end of the collar 10, and it is then rigidly anchored to the collar by means of a ferrule 13 which is inserted into the end of the tubular armor and is expanded to rigidly clamp the inner wall thereof. The body of the ferrule is slightly tapered, as shown in Fig. 3, to facilitate its being inserted into the tubular armor and then it is expanded by a suitable tool to rigidly clamp the armor against the inner wall of the collar 10. The outer end of the ferrule 13 is 35 provided with an outwardly extending flange 14

which when the ferrule is expanded, is clamped over and against the raw inner end of the tubular armor 12, the connection between this flange 14 and body of the ferrule being rounded so as to eliminate an annular cutting edge at this point, which cutting edge would be undesirable in that it would be liable to cut or rupture the fabric covering of the cord 8. In this way the flexible armor 12 is rigidly anchored to the cap 5 in such a manner that it can neither turn nor 10 pull out and also so that no rough edges will be left that would be likely to fray or cut the covering of the cable 8. In assembling, the parts 10, 12 and 13 are first properly assembled and then the inner end of the collar is moulded or cast 15 permanently into body cap 5.

Attached to the outer end of the flexible armor 12 is a pull-knob 15 in the form of a collar which surrounds the outer end of the armor and is attached thereto in the same manner that the 20 armor is attached to the collar 10 i. e., by means of a thimble 16 inserted into the outer end of the armor tube and expanded in a manner similar to the inner end of the thimble 13. The outer end of this thimble 16 is flanged outwardly 25 at 17 and this flange is clamped down over the raw edge of the armor tube and is countersunk into an annular recess in the collar-knob 15. The knob 15 is screwed onto the end of the armor tube in the same manner as the collar 10 is screwed 30 to the tube.

Where the handle is to be applied to the other, appliance-end of the cord, this is done in the manner shown in Fig. 4. I use the usual plug casing 18 which is divided longitudinally as usual 35 and clamped together by screws 19, this casing containing the usual binding screws for connection with the two wires of the cable. Instead, however, of casting or moulding the inner end of the collar 10 in the body 18 I clamp the same 40 therein sufficiently rigidly to avoid rotation in the casing 18. This casing 18 is as stated, usually made in two half sections so that it is an easy matter to clamp the inner end of the collar 10 45 between the halves of the casing by simply tightening the screws 19.

It will be understood that a feature of importance lies in the idea of screwing the end of the spiral flexible armor tube into a rigid collar-like member, such as the collar 10 or the pull-knob 50 15, and then rigidly anchoring it therein by an inserted ferrule which is expanded against the inner wall of the armor tube to thus clamp the armor tube against the collar-like member, it being important that the collar-like member 55

shall have sufficient strength to permit the ferrule to be expanded without cracking or rupturing the collar-like member.

In accordance with the provisions of the patent statutes, I have herein described the principle of operation of my invention, together with the apparatus which I now consider to represent the best embodiments thereof, but I desire to have it understood that the apparatus disclosed is only 10 illustrative and that the invention can be carried out by other means.

I claim:

1. In a device of the class set forth, a body, an unyielding collar threaded internally and having 15 one end embraced non-rotatively by said body, a flexible armor tube having an external thread and having one of its ends screwed into the threaded interior of said collar and extending to the inner end of said collar, and a metal ferrule 20 in the inner end of said flexible armor, this ferrule being deformed outwardly so as to rigidly and permanently clamp the inner end of said

flexible armor against the interior of said collar to thereby rigidly fasten the end of the armor tube to the collar.

2. The structure recited in claim 1, the inner annular edge of said ferrule being curved outwardly to not only cover the raw inner edge of the armor tube but also to provide an annular rounded edge which will avoid cutting the usual electric fabric-covered cord.

3. In a device of the class set forth, a rigid 10 body having a threaded passage therethrough, a flexible armor tube having external threads screwed into the threaded passage of said body, and a ferrule fitted into the end of said armor tube that lies within the body and deformed 15 permanently outwardly to rigidly and permanently clamp the armor tube against the threaded interior of the body to thereby permanently and rigidly clamp the end of the flexible armor to the body.

MICHAEL A. ROLLMAN.
